UNITED STATES PATENT OFFICE.

MIKE VARGO, OF YUKON, PENNSYLVANIA.

BALL RACK.

Application filed April 24, 1925. Serial No. 25,698.

To all whom it may concern:

Be it known that I, MIKE VARGO, a citizen of the United States, residing at Yukon, in the county of Westmoreland and State of Pennsylvania, have invented new and useful Improvements in Ball Racks, of which the following is a specification.

This invention relates to ball racks, and more particularly to a rack intended for 10 reception of pool balls.

One of the main objects of the invention is to provide a rack of simple construction which occupies but little space and may, if desired, be mounted directly upon the end 15 of the pool table. A further object is to provide a rack of this character having simple and efficient means for holding the balls on the shelves of the rack and for releasing the balls to permit the same to be discharged into a basket or suitable receptacle 20 positioned centrally of the rack. Further objects will appear from the detail description.

In the drawings:—

- 25 Figure 1 is a front view of the rack;
- Figure 2 is a section taken substantially on line 2—2 of Fig. 1;
- Figure 3 is a section taken substantially on line 3—3 of Fig. 1;
- 30 Figure 4 is an end view of the rack.
- The rack includes a casing 1 of boxlike construction in which are mounted shelves 2. A plate 3 is secured at the central portion of the front of the casing, the space beneath 35 the shelves and this plate being divided into a central compartment 4 and two end compartments 4^a. The end compartments 4^a are intended for reception of brushes or rubbers, and other articles used in cleaning 40 the pool table and the covering thereof. The central compartment 4 is for reception of a suitable basket or other receptacle, not shown, into which the balls are discharged from the shelves 2. A U-shaped yoke 6 is 45 slidably mounted through plate 3, the arms of this yoke sliding through suitable bushings 5 secured through the plate by nuts 5^b. Yoke 6 is normally held in its outer operative position by an expansion coil 50 spring 7 which is mounted about a central rod 8 projecting inwardly from yoke 6 and slidably through a bushing 5^a secured through plate 3 by a nut 5^c, outward movement of this rod being limited by a cotter 55 pin 9 inserted therethrough, or in any other suitable or preferred manner. Flat bars

10 are rigidly secured to the inner ends of the arms of yoke 6. These bars are disposed vertically and operate in grooves 11 and 12 provided in the top 1^a of casing 1 60 and the lower shelves 2, respectively. When the yoke is projected the bars 10 are positioned at the transverse centers of shelves 2 which are provided in their upper faces with grooves 2^a for reception of the balls b, 65 these grooves increasing in depth toward the center of the casing so as to provide supporting surfaces for the balls which are inclined downwardly and inwardly of the casing. Preferably, though not necessarily, 70 discs 12^a of felt or other suitable cushioning material are secured to bar 10 by means of screws 13, or in any other suitable or preferred manner, these discs being positioned to contact with the balls b at the centers 75 thereof. The shelves 2 are so spaced relative to each other and to top wall 1^a of the casing as to permit the balls to be readily placed on the shelves through suitably disposed openings 14 provided through the 80 end walls of the casing for this purpose.

The balls, when placed upon the shelves, travel by gravity toward the central portion of the rack, the inner ball on each shelf contacting with disc 12. When it is desired to remove the balls from the rack a basket or suitable receptacle is placed in compartment 4 and the yoke 6 is pushed inwardly so as to move the bars 10 rearwardly of the casing a sufficient distance to 85 move the discs 12 out of the path of travel of the balls b thus permitting the balls to travel by gravity off of the inner ends of the shelves, the balls being discharged into the basket. When yoke 6 is released it is 90 returned to operative position by means of 95 spring 7.

What I claim is:—

1. In a ball rack, a casing, shelves mounted in the casing and having ball supporting 100 surfaces inclined downwardly and inwardly of the casing, a plate mounted in front of the shelves adjacent the lower ends of the inclined surfaces thereof, a member slidably mounted through the plate, and means urging said member outwardly through the plate, outward movement of the slidably mounted member being positively limited, a retaining bar secured to said slidably mounted member and normally positioned to retain balls on the shelves, said bar being moved out of the path of travel of the balls 105
- 110

- to permit discharge thereof from the lower ends of the shelves when the slidably mounted member is forced inwardly through the plate.
5. 2. In a ball rack, a casing, shelves mounted in the casing at each end thereof and having ball supporting surfaces inclined downwardly and inwardly of the casing, a plate supported in front of the shelves at 10 the inner ends thereof, a yoke slidable through the plate, means for urging the yoke outwardly of the plate, means for limiting outward movement of the yoke, and retaining members carried by the arms of the 15 yoke and positioned to retain balls on the shelves when the yoke is in its normal outermost position, said members being moved out of the path of travel of the balls to permit the latter to be discharged from the shelves 20 when the yoke is forced inwardly through the plate.
3. In a ball rack, a casing, shelves mount-
- ed in the casing at each end thereof and having ball supporting surfaces inclined downwardly and inwardly of the casing, a 25 plate mounted in front of the shelves adjacent the inner ends thereof, a yoke slidably mounted through the plate, a rod extending from the yoke centrally thereof and slidable through the plate, means limiting outward 30 movement of the rod, an expansion coil spring mounted about said rod and confined between the plate and the yoke and acting to normally hold the yoke in its outermost position, and ball retaining members carried 35 by the arms of the yoke and disposed to retain balls on the shelves when the yoke is in its outermost position, said members being moved out of the path of travel of the balls to permit discharge thereof from the shelves 40 when the yoke is forced inwardly into its innermost position.

In testimony whereof I affix my signature.
MIKE VARGO.
